UNITED STATES PATENT OFFICE.

ISAAC E. PALMER, OF MIDDLETON, CONNECTICUT.

MACHINE FOR TENTERING, STRAIGHTENING, AND FINISHING WOVEN FABRICS.

SPECIFICATION forming part of Letters Patent No. 416,343, dated December 3, 1889.

Application filed June 30, 1884. Serial No. 136,340. (No model.)

To all whom it may concern:

Be it known that I, ISAAC E. PALMER, of Middletown, in the county of Middlesex and State of Connecticut, have invented a certain 5 new and useful Improvement in Machines for Tentering, Straightening, and Finishing Woven Fabrics, of which the following is a specification.

I will describe in detail a machine embodying my improvement, and then point out the novel features in claims.

In the accompanying drawings, Figure 1 is a side view of a machine wherein the fabric is stretched by diverging selvage-carrying 15 wheels or rotary rims, the drawing including only a single drying-cylinder, and also including a spreading mechanism, through which the fabric is conducted to the selvage-carrying wheels or rims. Fig. 2 is a front elevation of 20 the machine, the spreader mechanism being removed to illustrate more clearly the machine proper. Fig. 3 is a plan of the machine, including the spreader mechanism. Fig. 4 is a partial side view and vertical section in the 25 plane of rotation of one of the selvage-carrying rims, and wherein are located the trunnions on which the selvage-carrying rims oscillate. Fig. 4* is a horizontal section on the dotted line $y y$, Fig. 4. Fig. 5 is a partly-sectional view on the dotted line $x x$, Fig. 4. Fig. 6 is a sectional view of a part of the machine, very similar to Fig. 5, but having the trunnions on which the wheel or rim oscillates at one side of the plane of rotation, so 30 that at the points of feeding and delivery the selvages of the fabric will have a slight reciprocating movement. Fig. 7 designates a transverse section of a delivery-roller and a portion of a pivoted frame to be used there- 35 with in the example of my invention shown in Fig. 6. Fig. 8 is a plan of such roller and its supports. Fig. 9 is a detail view illustrating means whereby the trunnion-centers on which the selvage wheels or rims oscillate can 40 be adjusted into the plane of rotation, or more or less out therefrom. Fig. 10 is a sectional view of parts shown in Fig. 9. Fig. 11 is a plan of such parts of a long endless chain machine as embody my invention; and Fig. 45 50 12 is a transverse vertical section on the dotted line $z z$, Fig. 11, with parts in elevation.

Similar letters of reference designate corresponding parts in all the figures.

I will first describe the machine shown by Figs. 1 to 5, all inclusive.

A designates the bed or shears of the machine, which is supported by leg frames or stands A', and which is provided at the top with gibbed ways a, whereon are fitted two base-plates B B', which are capable of sliding 60 thereon toward and from each other.

The base-plates B B' are slightly rabbeted at *, to fit the outer edges of the ways, and are provided with pins a', having beveled faces which catch under the beveled edges of 65 the guides or ways a, and so prevent rising movement of the said base-plates. The said base-plates B B' are moved toward and from each other by means of a screw-shaft B², which may be turned by a crank b at either 70 end, and which is mounted in bearings b'. On the screw-shaft B² are right and left hand threads which engage with nuts b² on the base-plates B B', as best shown in Fig. 2, and thereby the two base-plates and the super- 75 posed mechanism may be moved toward and from each other to operate upon goods of greater or less width.

Upon each base-plate B B' is an upwardly-projecting pivot or fulcrum b³, which in this 80 instance is near the front of the machine, and upon this pivot is fulcrumed a frame plate or carriage C, constructed with an eye or hub b⁴, fitting the pivot and capable of swinging upon said pivot in a horizontal 85 plane, as more fully hereinafter described.

Each frame or carriage C has mounted upon it a selvage-carrying wheel or rim, which in this example of my invention has not only a progressive rotary motion, but also an oscillating or vibrating motion in a direction transverse to its plane of rotation. The selvage-carrying wheels or rims might be provided with card clothing or tenter-pins to hold the selvages of the fabric—as, for instance, as shown in my Reissued Letters Patent No. 8,978, dated November 25, 1879; but I deem it most desirable to employ in connection with them belts or moving bands, which hold the selvages upon them and have a progressive movement encircling about half the periphery of the rims.

A detailed description of the selvage-carrying devices will best be understood by reference to Figs. 1, 4, and 5.

Each wheel or rim *c* has an inwardly-projecting annular flange or web *c**, to which are bolted a number of sections *c*', forming a complete ring having a rounded groove or channel *c*² in its inner periphery. The parts *c* *c*' constitute the only rotary parts of the wheel or rim, and are supported while rotating by a number of shoes or stationary blocks *c*³, which are here shown as three in number for each rim. The shoes or blocks *c*³ are each held between a pair of jaws *c*⁴ *c*⁴, which are hinged at *c*⁵, and which may be tightened upon the interposed shoe by a bolt *c*⁶. The clamping-jaws are secured by the bolt *c*⁶ to the outwardly-projecting annular flange or web *c*⁷ of a center frame or ring *D*, which is non-rotary and is of T shape in transverse section.

Upon the carriage or frame *C*, inside of and outside of the center frame *D*, are erected standards *d*, which are divided to accommodate the rim *c*, and which are received in notches *c*⁸* at diametrically-opposite points in the center frame, and at these points the center frame is supported by trunnions *d*', which may consist of screws fixed adjustably in the cross portions of the standards *d*, and entering sockets or bearings formed in the center frame *D*, as best shown in Fig. 4. From the foregoing it will be seen that the rim *c* may turn freely about the center frame *D*, and that the trunnions *d*' constitute a support for the frame *D*, and consequently for the selvage-carrying devices, which is maintained against lateral reciprocation and which provides for the oscillation or vibration of the frame *D* and the rim *c*. It will further be seen, by reference more particularly to Fig. 4, that the supports for the frame *D* are arranged near the feed and delivery points for the fabric *s*, and that consequently little or no reciprocation of the fabric occurs at these points, whereby the fabric is caused to be fed to and delivered from the machine in approximately straight lines.

Although the means for supporting the selvage-carrying rims *c* is very desirable, I do not confine myself thereto, as other constructions and arrangements of supports may be employed to a like end.

In connection with each carrying-rim *c*, I employ an endless band *e*, which is mounted on pulleys or wheels *e*' *e*² *e*³ *e*⁴, and encircles or embraces about half the circumference of the rim *c*. In the rim *c* is a concave seat or half-round circumferential groove *c*⁸, and on that face of the belt or band *e* which comes next to the rim are teeth or projections which fill said groove snugly. These teeth or projections may consist of small pieces of brass having prongs, roots, or spurs which are driven through the belt or band and clinched. The pulleys or wheels *e*' *e*³ for the band *e* are

here shown as journaled upon brackets *e*⁴ *e*⁵, which are bolted to and oscillate or vibrate with the center frame *D* and rim *c*; and the two pulleys *e*² *e*² constitute idler-pulleys and may be moved to tighten the belt or band. To the upper part of the center frame *D* is bolted a plate or forked upright *e*⁶, and *e*⁷ designates a double bracket or frame which is fitted to slide up and down in the fork of the plate or upright *e*⁶, and has its two diverging branches *e*⁷ *e*⁷ mortised at *e*⁸* to fit and receive through them the straight portions of the forked plates *e*⁶. The two branches of the double bracket *e*⁷ carry the idler or tension pulleys *e*² *e*², and may be raised by a screw *e*⁸, to put tension on the belt or band *e*. The end of the adjusting-screw *e*⁸ is square, to provide for applying a wrench, and a collar *e*⁹ thereon rests against a lug or ear *e*⁹* on the plate *e*⁶, and forms a thrust-bearing. The same bracket *e*⁷ which carries or supports the pulley or wheel *e*³ also supports a second wheel or pulley *e*¹⁰, on the shaft of which is a pinion *e*¹¹, gearing with a pinion *e*¹² on the same shaft with the pulley *e*³, and thus rotary motion imparted to the pulleys *e*¹⁰, by means hereinafter described, is transmitted to the pulley *e*³, and a progressive motion is given the band *e*.

At each end of the bed *A* are a pair of uprights or standards *f* *f*', which are braced and connected by cross-rods *f**. To the two uprights or standards *f* at the front of the machine is journaled a feed-roll or a roll *f*², under which the fabric *s* passes to the machine, and said roll is composed of short sections capable of turning independently of each other on a common shaft or rod. To the standards *f*', at the back of the machine, is journaled a delivery-roll *D*', under which the fabric passes, and is delivered to a drying-cylinder *E*, which may be the first of a series. The cylinder *E*, or series of cylinders, constitute fabric-carrying devices, whereby the fabric is held extended during drying, and which are supported so as to preserve and produce the direct travel of the fabric in a straight line during the latter portion of its movement through the machine. This drying-cylinder and the remainder of the series (not shown) may be heated by steam introduced through its journals or in any other suitable way, and the construction and arrangement of such cylinders are well understood by persons skilled in the art. As here shown, the cylinder is rotated by a pinion and gear wheel *f*³ *f*⁴ from a shaft *f*⁵, to which rotary motion is imparted by a belt *f*⁶ from the driving-shaft *f*⁷, which is journaled in the end or leg frames *A*'.

The fabric *s* may be spread out by the feeders or attendants standing at the two selvage-carrying rims *c*; but I deem it desirable to subject it to a preliminary opening or spreading operation while on its way to the attendants, because it relieves them of a considerable amount of work and leaves them to give

their undivided attention to feeding the fabric to the selvage-carrying rims and to do that work more perfectly.

I have here represented a spreading mechanism which comprises two shafts or bars f^8 f^9 , grooved or ribbed spirally throughout their length, and having reversed pitch from the middle of their length toward opposite ends. The bar or shaft f^8 is journaled in swinging frames f^{10} , fulcrumed at f^{11} in standards f^{12} , and having an adjustable connection with said standards consisting of a curved or slotted arm f^{13} and a clamping-screw f^{14} . The spreading rod or shaft f^9 is carried in swinging frames f^{15} , fulcrumed at f^{16} to the standards f , and made adjustable by means of a curved and slotted arm f^{17} and clamping-screw f^{18} or other suitable means. In the standards f^{12} is journaled a sectional roller f^{24} , composed of short roll-sections capable of turning independently of each other upon a common rod or shaft. The fabric s is carried over the sectional roller f^{24} , under the spreading rod or shaft f^8 , and then over the spreading rod or shaft f^9 and under the sectional roller f^2 and to the selvage-carrying rims c . The two spreading rods or shafts are connected by a belt f^{19} and pulleys f^{20} , so that the rotation of both rods or shafts is insured.

Beneath the pivots b^3 , and near the front of the machine, are two shafts F F , on which are reversely set cone-pulleys g g' , and which are rotated by belts g g' , driven from reversed cones g^2 g^2 on the driving-shaft f^7 . These belts g' are crossed so as to bring both driving portions of the belt on the pulleys g g^2 on the under sides thereof, and each belt is controlled by a shifter g^3 , which is attached to a frame adapted to slide along a rod or fixed bar g^4 and having a spur-rack g^5 . Upon a rod g^6 extending lengthwise of the machine are two frames g^7 , each comprising bearings for a belt-shifting shaft g^8 , on the inner end of which is a pinion g^9 , engaging with the rack g^5 , and on the other end of which is a foot-roll g^{10} , whereby the shaft may be turned to move the shippers g^3 , and thereby to shift the belts g' to drive one shaft F to a variable degree faster or slower than the other shaft F . Each shaft F is mounted in a bearing g^{11} depending from the bed A , and is held against longitudinal movement by a collar g^* on one side of this bearing and the cone-pulley g on the other side thereof. From each base-plate B B' depends a bearing g^{12} , which may move along the shaft, and in which is fitted the sleeve or hub g^{14} of a pulley g^{13} . This hub or sleeve g^{14} rotates freely in the bearing g^{12} , and is confined against longitudinal movement in its bearing, and is engaged by a groove and a feather with the shaft F , so that it can slide along the shaft, but will always turn therewith. From the hub or eye b^4 of each horizontal swinging frame or carriage there extends upward a standard h , on which are idler-pulleys h' h'' , and h^2 designates an endless driving-belt which encircles the pul-

ley g^{13} , and is deflected and properly directed by the idlers h' onto the pulley e^{10} , from which rotary motion is transmitted to the pulley e^3 , and thereby to the band or clamping-belt e , which confines the selvage on the rim c .

From the above description it will be understood that the swinging of the frames or carriages C upon their pivots b^3 provides for the adjustment of the selvage-carrying rims at different angles of divergence; but when the carriages are thus adjusted the plane of rotation of the idler-pulleys h' is correspondingly changed, owing to their standards h being carried by the frames or carriages C , and hence the belts h^2 will deflect over them properly. The distance between the pulleys g^{13} and idlers h' is sufficient to enable the belts h^2 to adjust themselves to their pulleys.

When the center frame D and the selvage-carrying rims c are oscillated or vibrated to and fro, the bands e and their supporting and driving pulleys all move with the center frame D ; but the angle formed by the planes of rotation of the pulley e^{10} and idler-pulleys h' is so slight that the length of belt h^2 between them compensates readily for such differences. In this example of my invention the two selvage-carrying rims c receive rotary motion from the engagement of the bands e with them; but it is not absolutely necessary to employ separate driving mechanism for the two bands, as here shown, although I deem it preferable, as then the movement of either selvage of the fabric may be increased or retarded relatively to the speed of the other. If for any reason such adjustment or variation of speed were not deemed of importance, a single long shaft could be substituted for the two shorter shafts F , and this long shaft might be driven from the driving-shaft f^7 by a single belt and cone-pulleys. In machines of this class it is customary to employ a stationary frame or drag between the selvage-carrying wheels or rims to support the body of the fabric. A drag or frame of any ordinary or suitable description may be used; but as I here make no claim thereto I have shown a drag of very simple form, which I will now describe.

G designates a standard erected on the bed A at the middle of its length and having an arched top, and upon the standards d , erected on each carriage C , are secured arches or frames G' . The bars G^2 of the drag are made in sections, and such sections are capable of sliding one on another to permit of the selvage-carrying rims being adjusted at different angles of divergence and to different distances apart. At the point where the sectional bars G^2 lap they are supported by the arched top of the standard G .

In lieu of the drag described, which is stationary, any description of stationary or movable drag or supporting-frame may be used.

I will now describe how a uniform tension and lateral stretching is produced in the fab-

- ric, even though the width of the fabric is not uniform, or in case of the same width of selvage not being always fed between the bands *e* and the rims *c*. To effect this result, 5 I employ balancing devices, which are shown as consisting of springs *H*, bent nearly into the form of a circle and placed around the eyes or hubs *b*⁴ of the carriages or laterally-swinging frames *C*, as best shown in Figs. 1, 10 2, 4, and 4*. One end *h*³ of each spring is secured fast to the base-plate *B* or *B'* by a pin or bolt, and the other end is adjustably secured by a thumb-screw *h*⁴ to the web of the carriage or swinging frame *C*. When applied 15 as shown, the springs exert a constant tendency to draw or move the two selvage-carrying rims or wheels away from each other by swinging the two frames or carriages *C* in opposite directions; but such movement or increase of divergence of the wheels or rims is resisted by the fabric which is between the two. The lateral pull of the fabric and the 20 tension of the springs therefore form two opposing forces, and the latter of these forces yields to the former and allows the wheels or rims to move slightly toward each other when the fabric between the wheels decreases slightly in width. At the delivery side of the 25 rims or wheels each carriage *C* is furnished with a pinion *i*, which is provided with a hand-wheel *i'*, whereby it may be turned, and which gears into a short rack *i*², formed upon or attached to the base-plate *B* or *B'*. The 30 journal for the pinion *i* is formed by a screw *i*³, which fits a screw-threaded socket *i*⁴ in the said carriage *C*, and may be turned by a handle *i*⁴, as best shown in Fig. 4.
- When the carriage is to be left free for self-adjustment, as above described, the screw *i*³ 35 is left slack enough, so that the pinion *i* may freely turn on it, and as the carriage swings on its pivot *b*³ the pinion *i* runs along the rack *i*² and rotates. When it is required to prevent such self-adjustment of the carriage, 40 the screw *i*³ is tightened up and clamps the pinion between its head and the carriage and thus prevents the turning of the pinion. The locking of the pinion in the rack prevents the carriage from moving on its pivot *b*³.
- 45 I have before described generally how I produce a lateral change in the direction of movement of the fabric, but such change will be more readily understood by reference to Fig. 3. As in other machines of this class, the drying-cylinder *E* and the feeding and delivery rolls *f*² *D'* are all substantially parallel. In prior machines of this class the selvage-carrying wheels or rims have been set inclined in opposite directions relatively 50 to a line drawn at right angles to the drying-cylinder.
- In Fig. 3 I have represented the selvage-carrying wheel or rim which is upon the base-plate *B* as inclined very slightly toward the 55 left from a line drawn at right angles to the drying-cylinder, and the other wheel or rim, which is upon the other base-plate *B'*, inclined

similarly, but in a far greater degree, thereby securing the divergence necessary to stretch the fabric properly. The fabric may be said 70 to be given its first direction as it passes under the feed-roll *f*² at the feeding-point, such direction being directly at right angles to the drying-cylinder. As the fabric is grasped by the selvage-carrying wheels or rims, its direction is shifted or diverted laterally toward 75 the left, and as the fabric passes under the delivery-roll *D'* and onto the drying-cylinder its direction is again changed or restored to a direction at right angles to the cylinder and 80 the fabric retains its straight direction of travel throughout its passage over the drying-cylinders.

I have before stated that the result is 85 greatly enhanced by reciprocating or vibrating the fabric laterally, and will now describe one means of accomplishing this result, reference being made more particularly to Figs. 1, 2, 4, and 5.

As before stated, the frame or body *D* of 90 each selvage-carrying rim *c* is capable of oscillating on the trunnions *d*' and imparting such a motion to the rotating rim *c*. Secured fast to each base-plate *B* *B'* is a standard *j*, forked or bifurcated at the top and having 95 fulcrumed or pivoted to it at its upper end *j*' a lever *k*, which extends outward and is capable of rising and falling motion upon the pivot *j*' as a center. To the upper and lower portions of the body or frame *D* is pivoted at 100 *j** a bail or yoke *I*, receiving through a socket or eye *j*² the lever *k*. To the outer end of each lever *k* is universally connected a pitman or eccentric rod *k*', at the lower end of which is an eccentric-strap *k**, fitting an eccentric *l* 105 on a shaft *J*. The shaft *J* is rotated by any suitable gearing—as, for example, by spur-wheels *l*' *l*² on the shafts *J* *f*⁷ and an idler-wheel *l*³—and the two eccentrics should be set at diametrically-opposite points. As here 110 shown, each eccentric *l* contains an inner adjustable section *l**, whereby the throw of the eccentrics may be varied. As shown in Fig. 4, the section *l** may be rotated within the eccentric *l*, and may be secured in any position to which it may be adjusted by means 115 of a key engaging semicircular grooves in the eccentric and the adjustable section. (Shown more clearly in Figs. 4 and 5.) The shaft *J* is longitudinally grooved and the eccentrics 120 are connected therewith by feathers, so that they may move along the shaft as the base-plates *B* *B'* are moved toward or from each other. As the shaft *J* rotates, the levers *k* impart an oscillating or vibrating movement, 125 through the bails *I*, to the center frames or bodies *D* in a direction at right angles to the plane of rotation of the selvage-carrying rims *c*, and the fabric thus receives a lateral reciprocating or vibrating movement between 130 the points of feed and delivery during its progressive movement. When the centers of the trunnions *d*', which constitute the centers of oscillation of the frames *D* and sel-

vage-carrying rims, lie in the same vertical plane as said rims, the points of feed and delivery of the fabric which are in the prolongation of the axes of the trunnions will be stationary; but by placing the center of the trunnions outside the planes of the selvage-rims the fabric may be given a reciprocating movement at the selvages alternately in reverse directions, and in addition to its 5 vibrating or lateral reciprocating movement. The feed and delivery points at opposite selvages would then rise and fall and the delivery-roll D' may be so hung and supported as to allow it to tilt vertically in the 10 plane of its axis. I have shown such an arrangement of parts in Figs. 6, 7, and 8. In this example of my invention the same letters of reference designate the same parts as in my previous description. In this case the 15 center of oscillation of the selvage-rim c is not opposite or in the same vertical plane with the circumferential groove or seat c^8 therein, but is nearer the middle of the machine, and consequently the rising and falling movement of the lever k will oscillate the rim and will produce a rising and falling movement at the points of feeding and delivery. The delivery-roll D' is here shown 20 as journaled in opposite ends of a frame D^2 , which is pivoted by a bolt m at about the middle of its length to a bar or stretcher D^3 , extending between the uprights or standards f' . The roll-frame D^2 can oscillate on its pivot m to allow the ends of the roll to rise 25 and fall alternately. In order to prevent undue rising movement of either end of the roll-frame D^2 , I provide the stretcher or rail D^3 with guards or abutments m' , which extend over the end portions of the roll-frame 30 D^2 and form stops thereto.

In some cases it may be desirable to provide a machine which can be adjusted to produce a simple lateral reciprocation of the fabric, or such movement, and, in addition 35 thereto, a reciprocation of the selvages alternately in reverse directions at or near the feed and delivery points. I have shown in Figs. 9 and 10 an example of trunnion-bearing 40 whereby such adjustment may be effected. In the standard d and center frame D are formed cylindric sockets or holes n n' , wherein are fitted plugs or sleeves n^2 n^3 . These plugs or sleeves can be adjusted circumferentially and held by set-screws n^* against 45 shifting. They are connected by a trunnion-pin d' , as shown in Fig. 10, which forms the center of oscillation and is eccentric to the sleeves or plugs n^2 n^3 . When the parts are adjusted to the position shown in Fig. 10, the 50 trunnion d' is in the plane of rotation of the selvage-carrying rim c , and an oscillating movement of the rim will not produce any rising and falling of the feeding and delivery points. When the plugs or sleeves n^2 n^3 55 are turned half round and there secured, the trunnion d' will be to the left of the plane of rotation of the selvage-carrying rim c , and

consequently an oscillating movement thereof will produce also a rising and falling of the points of feed and delivery and an alternate 70 and longitudinal reciprocation of the selvages.

Figs. 11 and 12 represent only such parts of a chain-machine as are necessary to illustrate my invention. K K designate endless 75 chains or bands, which may be provided with tenter pins or nippers for grasping or holding the selvages of a fabric. These chains or bands are driven by wheels o o on a shaft o' . The chains or bands K are guided by tracks 80 or ways, constituting supports, here shown as composed of sections L L , L' L' , and L^2 L^2 . The sections L L are divergent, and by them the stretching and bringing of the fabric to full width is effected. The sections L' L' and L^2 85 L^2 are parallel. At the feeding end of the machine are idlers p p for the chains, supported in bearings on the sections L . The sections L' L' L^2 of the tracks or guides are pivotally connected at their ends to cross-bars 90 L^3 L^4 L^5 , and the cross-bars L^3 L^5 are pivoted at q to posts or other supports q' . The cross-bar L^4 is capable of being reciprocated by a connecting-rod and crank r r' . The rod r is pivotally connected with the cross-bar L^4 , and 95 has an extensive bearing-surface r^2 on a column M . The crank r' is on a vertical shaft r^3 , which is supported by an extension m' of a column m , and rotated by bevel-wheels r^4 from a horizontal shaft r^5 . A section L^2 of 100 the track or guide has a projection or arm r^6 , connected by a rod r^7 with the crank r' , and hence it will be seen that the crank r' imparts both a lateral reciprocation and a longitudinal reciprocation to the tracks or guides. 105

It will be understood that the sections L L' , or analogous sections of guides at or near the entering end of the machine, are alone reciprocated laterally, and that the sections L^2 , and other sections nearer the delivery end of 110 the machine, are held so as to preserve the straight run or travel of the fabric.

For driving the shaft o' it is necessary to employ mechanism which will permit the shaft to swing slightly as the tracks or guides 115 are reciprocated longitudinally. Such mechanism is common in machines of this class.

It will be seen that the bars L^3 L^5 constitute supports for the supports L L' , and are maintained against lateral reciprocation, and, 120 through the pivotal connection therewith of the supports L L' , admit of the lateral reciprocation of the latter. The supports L^3 L^5 , being at the feed and delivery points for the fabric to and from the laterally-reciprocating 125 supports L L' , there will be little or no reciprocation of the fabric at the feed or delivery points, but the same will be fed and delivered in approximately straight lines.

I have here shown a vertical shaft o^2 geared 130 by bevel-wheels o^3 with the shaft o' and receiving motion by bevel-wheels o^4 from a shaft o^5 . The shafts o^2 and o^5 have bearings in a standard o^6 , and on the upper portion

thereof is fitted a yoke or frame o^7 , which is capable of swinging freely, and in which are provided bearings o^8 for the shaft o^9 . The center of oscillation of the shaft o^9 is therefore concentric with the vertical shaft o^2 . By means of the crank and connecting-rods the fabric, which is carried by the chains through the laterally-reciprocating guides, tracks, or ways, will be subjected to a lateral reciprocating or vibratory movement and a longitudinal reciprocation of the selvages during its forward and progressive movement, and therefore has its direction of movement changed laterally.

- 15 In Fig. 5 I have represented the selvage-carrying rims c as at the middle of their vibrating or oscillating movement, the two eccentrics l being at half-stroke. If desired, the shaft J may be stopped when the eccentrics are at opposite ends of their stroke, and their rims c will then be held in inclined positions in planes coincident with their axes of rotation, both rims being canted or inclined in the same direction from the perpendicular. If held in such inclined or canted positions, it is obvious that another lateral change in the direction of movement of the fabric would be produced between the points of feed and delivery. This would be true even if the rims c were set equally divergent in opposite directions from a center line at right angles to the drying-cylinder, and were also set canting or inclined vertically, as above described. It is advantageous to employ the selvage-carrying rims provided with circumferential grooves and bands having projections entering said grooves, because then the fabric is held more firmly with a bite upon a less width of selvage, and the band and selvage are prevented from slipping laterally off the said rim. I have here represented the selvage-carrying rims as receiving rotary motion through the progressive motion of the bands e , but in some cases the rims and bands may have no movement of themselves and be left free to be moved by the pull or drag of the fabric as it is drawn forward by the drying-cylinder.

I may, if desired, provide the selvage-carrying rims each with a circumferential rib or projection in lieu of a groove, and in such case the bands e would each have a groove fitting such rib or projection.

What I claim as my invention, and desire to secure by Letters Patent, is—

1. The combination of selvage-carrying devices, supports for said selvage-carrying devices, and mechanism, substantially such as described, for imparting laterally-reciprocating movement to said selvage-carrying devices, said supports operating to support the selvage-carrying devices near the point of delivery for the fabric, whereby the reciprocation of the fabric at that point will be avoided, substantially as specified.

2. The combination of selvage-carrying devices, supports for said selvage-carrying de-

vices, mechanism, substantially such as described, for imparting laterally-reciprocating movements to said selvage-carrying devices, 70 and a non-reciprocating roller about which the fabric passes in its delivery from the selvage-carrying devices, substantially as specified.

3. The combination, with rotary selvage-carrying devices arranged upon opposite sides of the machine, of carriages upon which said selvage-carrying devices are mounted, movable toward and from each other to vary the degree of divergence of said devices, and 80 springs operating upon said carriages to move them away from each other automatically, and thus produce the desired tension on the fabric while progressive movement is being imparted to the selvage-carrying devices, substantially as specified.

4. The combination, with selvage-carrying devices arranged upon opposite sides of the machine, of carriages upon which said selvage-carrying devices are mounted, movable 90 toward and from each other to vary the degree of divergence of said devices, springs operating upon said carriages to move them away from each other automatically to produce the desired tension on the fabric, and 95 locks for holding the selvage-carrying devices against movement toward and from each other and rendering said springs inoperative, when desired, substantially as specified.

5. The combination, with rotary selvage-carrying rims provided with devices, substantially as described, for holding a fabric upon them, of non-rotary center frames, whereon said rims may turn, trunnions upon which said frames are supported and which permit of their oscillation, and devices, substantially as described, connected with said center frames for imparting to them and to the rims maintained by them an oscillating or vibrating movement during the progressive rotary motion of said rims, substantially as herein described.

6. The combination, with rotary selvage-carrying rims or wheels provided with devices, substantially as described, for holding the fabric upon them, of non-rotary frames, whereon said rims or wheels may turn, and which have trunnions permitting of their oscillation in directions at right angles to the planes of rotation of the rims or wheels, and eccentrics and connections, through which an oscillating or vibrating movement is imparted to the non-rotary frames and the rims or wheels turning on them, substantially as herein described.

7. The combination, with rotary selvage-carrying rims c , provided with devices, substantially as described, for holding a fabric upon them, of non-rotary center frames D , 130 trunnion-supports d' for said frames, bails I , connected with the top and bottom of said frames and projecting outward therefrom, standards j , levers k , fulcrumed at j' , and con-

nected with said bails, eccentrics and eccentric-rods for operating said levers *k*, a shaft *J* for said eccentrics, and means for rotating said shaft, substantially as herein described.

5 8. The combination, with the rotary selvage-carrying-rims *c c*, provided with devices, substantially as described, for holding a fabric upon them, of non-rotary center frames *D*, trunnion-supports *d'* for said frames, bails *I*, pivoted to said frames at *j*, standards *j*, levers *k*, fulcrumed at *j'* and connected with said bails, eccentrics *l*, and rods *k'* for operating said levers *k*, a shaft *J* for said eccentrics, and means for rotating said shaft, all 15 substantially as herein described.

9. The combination, with rotary selvage-carrying rims provided with devices, substantially as described, for holding the fabric upon them, of non-rotary frames whereon said 20 rims may turn, and which have trunnions arranged at one side of or eccentric to the planes of rotation of said rims, and devices, substantially as described, for imparting to said frames and the rims turning upon them an 25 oscillating or vibrating motion, whereby such rims have a rising and falling movement simultaneously with their rotary motion, substantially as herein described.

10. The combination, with rotary selvage-carrying rims or wheels provided with devices, substantially as described, for holding a fabric upon them, of non-rotary frames whereon said rims may turn, and which are provided with trunnions, frames for said trunnions rotatably adjustable to bring the centers of oscillation of said non-rotary frames coincident with or eccentric to the planes of rotation of said rims, and devices, substantially as described, for imparting an oscillating or vibrating motion to said non-rotary frames and the rims or wheels turning on them, substantially as specified.

11. The combination, with rotary selvage-carrying rims or wheels provided with means, substantially as described, for holding a fabric upon them, of non-rotary frames whereon said rims may be turned, and which have trunnions arranged at one side of or eccentric to the planes of rotation of said rims or wheels, devices, substantially as described, for imparting to such frames and the rims or wheels an oscillating or vibrating motion, a delivery-roller below which said fabric passes as it leaves the rims or wheels, and bearings for said roller which permit the alternate rising and falling of its ends, substantially as described.

12. The combination, with rotary selvage-carrying rims provided with means, substantially as described, for holding a fabric upon them, of non-rotary center frames whereon said rims may turn, trunnions for said frames arranged at one side of or eccentric to the planes of rotation of said rims, devices, substantially as described, for imparting to said frames and the rims turning upon them an oscillating or vibrating movement, the de-

livery-roll *D'*, the roll-frame *D²*, carrying bearings at opposite ends, and a support to which said roll-frame is pivoted between its 70 ends to provide for its movement in a vertical plane, substantially as herein described.

13. The combination, with a bed plate or frame, of two base-plates movable thereon toward and from each other, carriages pivoted to the said base-plates, and selvage-carrying wheels or rims mounted upon said carriages, means, substantially such as described, for adjusting said carrying wheels or rims with said carriages at different angles of 80 divergence, springs acting upon said carriages and applied to exert a constant tendency to increase the angle of divergence of said wheels or rims against the lateral tension of the fabric, and mechanism, substantially as described, for positively rotating said wheels or rims, substantially as specified.

14. The combination, with a bed plate or frame, of two base-plates movable thereon toward and from each other, selvage-carrying 90 wheels or rims, carriages each supporting a selvage-carrying wheel or rim and pivoted to a base-plate at the front of the machine and below the feeding-point, springs applied to said carriages for exerting a constant 95 tendency to move such carriages away from each other at the point of delivery and against the lateral tension on the fabric, and mechanism, substantially as described, for positively rotating the wheels or rims, substantially as herein specified.

15. The combination of the bed *A*, the base-plates *B B'*, the screw-shaft *B²*, for moving said base-plates, the pivots *b³*, the swinging carriages *C C*, having sockets *b⁴*, selvage-carrying wheels or rims upon said carriages, and the springs *H*, each attached at one end to a base-plate and at the other end to a carriage *C*, all substantially as herein described.

16. The combination of the bed *A*, the base-plates *B B'*, the pivots *b³*, the carriages *C C*, having sockets *b⁴*, selvage-carrying wheels or rims upon said carriages, racks upon the sides of the base-plates opposite said pivots, pinions on said carriages engaging said racks, 115 springs for moving said carriages away from each other, and devices for locking said pinions against turning, whereby the springs will be rendered inoperative, substantially as herein described.

17. The combination of the bed *A*, the base-plates *B B'*, the pivots *b³* at the front of said base-plates, and the racks *i²* at the back thereof, the carriages *C C*, having sockets *b⁴* and screws *i³*, the pinions *i*, engaging with 125 said racks and journaled upon said screws, selvage-carrying wheels or rims upon said carriages, and springs applied to said carriages for moving them away from each other, substantially as herein described.

18. In a machine for fentering, straightening, and finishing fabrics, the combination, with diverging rotary selvage-carrying wheels or rims on opposite sides of the machine

capable of movement toward and from each other, of movable carriages for said wheels or rims, bands partly encircling said wheels or rims for confining the selvages of a fabric thereon, and means for producing a positive progressive movement of said bands, and through them rotating said wheels or rims, substantially as herein described.

19. The combination, with two diverging and rotary selvage-carrying wheels or rims, a bed-plate A, base-plates movable toward and from each other, carriages pivoted upon and movable with said base-plates, and standards erected on said carriages and serving to support said wheels or rims, of driving-pulleys arranged below the pivots of said carriages, other pulleys e^3 , devices, substantially as described, through which the last-mentioned pulleys impart rotary motion to the selvage-carrying wheels or rims, idlers supported from said carriages, and driving-belts passing from said driving-pulleys upward over said idlers and thence around the pulleys from which the selvage-carrying wheels or rims receive their rotary motion, substantially as herein described.

20. The combination, with diverging selvage-carrying wheels or rims, a bed A, base-plates B B' thereon, and pivoted carriages C C, supporting said wheels or rims, of the bands e and the pulleys $e' e^2 e^3$, the pulley e^{10} and gears $e^{11} e^{12}$, the standards h and their idlers h' , the driving-pulleys g^{13} , and the endless belts h^2 , passing around said pulleys g^{13} , over the idlers h' and around the pulleys e^{10} , all substantially as herein described.

21. The combination, with the rotary diverging selvage-carrying wheels or rims of a

machine for tentering, straightening, and finishing fabrics, of the feed-roll f^2 , under which the fabric is passed to the said wheels or rims, and which is composed of independently-rotating sections, substantially as herein described.

22. The combination, with the rotary diverging selvage-carrying wheels or rims, of a feed-roll, under which the fabric is passed to said wheels or rims, a rotary spreading-bar f^9 , over which the fabric passes to the roll, and supports for said spreading-bar f^9 , providing for its circumferential adjustment around said feed-roller, substantially as herein described.

23. The combination, with the rotary diverging selvage-carrying wheels or rims, of the rolls $f^{2*} f^2$, over and under which the fabric passes, the rotary spreading-bars $f^8 f^9$, under and over which the fabric passes, and adjustable supports for said spreading-bars $f^8 f^9$, all substantially as herein described.

24. The combination, with diverging rotary selvage-carrying rims or wheels on opposite sides of the machine provided with circumferential grooves or seats, of endless bands for confining the selvages of a fabric upon said rims or wheels, provided on their faces which bear directly on the rim with projections made independently from but secured to said bands and fitting said grooves or seats, and pulleys for supporting and directing said bands, substantially as herein described.
